DOLL

Herbert S. Lenhart, 12 Everett Place, Halesite, N.Y.

Filed Mar. 24, 1964, Ser. No. 79,151

Term of patent 14 years

(Cl. D34—4)

FIG. 1

FIG. 2

FIG. 3

FIG. 4

FIG. 5

FIG. 7

FIG. 6

FIG. 1 is a front view of a doll showing my design;
FIG. 2 is a rear or back view thereof;

FIG. 3 is a side view thereof with the opposite side
being the same;

FIG. 4 is a top plan view thereof;

FIG. 5 is a bottom plan view thereof;

FIG. 6 is a section taken through line 6—6 of FIG. 1;
and

FIG. 7 is a perspective view thereof.

I claim:

The ornamental design for a doll, substantially as shown and described.
